UNITED STATES PATENT OFFICE.

WILLIAM F. BLANCHET, OF HAYWARDS, CALIFORNIA, ASSIGNOR OF ONE-HALF TO THOMAS C. CREIGHTON, OF SAME PLACE, HENRY F. MARSH, JR., OF ALAMEDA, AND ARTHUR KIDD, OF SAN FRANCISCO, CALIFORNIA.

KEY-FASTENER.

SPECIFICATION forming part of Letters Patent No. 577,504, dated February 23, 1897.

Application filed March 14, 1896. Serial No. 583,238. (No model.)

To all whom it may concern:

Be it known that I, WILLIAM F. BLANCHET, a citizen of the United States, residing at Haywards, in the county of Alameda and State 5 of California, have invented certain new and useful Improvements in Key-Fasteners for Door-Locks, of which the following is a specification.

My invention relates to improvements made 10 in devices for confining a door-key in its lock in such manner that when the door is closed and the bolt of the lock is thrown the key cannot be turned from the outside by the use of nippers or other lock-picking instruments. 15 The object of this invention is the production of a device or attachment capable of being applied to the escutcheon-plate of most any of the present styles of door-locks now in the market, and possessing the function or 20 quality of gripping the key with a power or force that increases under any attempt to turn the key backward.

To such ends and object my said invention consists in a gripping-plate of peculiar form 25 and the combination thereof, with the escutcheon-plate, of a door-lock and with a key having a concave portion on its shank adapted to engage the edge of said gripping-plate, the same being constructed and applied for 30 operation as hereinafter fully explained and set forth.

The following description explains at length the manner in which I proceed to construct and apply the said invention, reference being 35 had to the drawings that accompany and form part of this specification.

In the said drawings, Figure 1 represents in front view the escutcheon-plate of a door-lock having my improved key-fastener 40 secured to it, the said device being turned into the position which it assumes when the key is to be introduced or removed from the lock. Fig. 2 is a similar front view representing the fastener turned into working position to 45 turn the key, which has previously been inserted and turned in the lock, the shank of the key being indicated in cross-section. Fig. 3 illustrates the position of the device when turned down to act as an escutcheon or cover 50 for the keyhole after the key is removed.

Fig. 4 is a front view, on an enlarged scale, of the fastener and the lower portion of the escutcheon-plate to which it is pivoted, the fastener being turned into position against the shank of the key, which is shown in cross-section cut off close to the face of the escutcheon-plate. Figs. 5 and 6 are detail views of the key, showing the concave portion on the shank of the key, Fig. 6 being a cross-section at xx , Fig. 5.

A indicates the escutcheon-plate of a mortise-lock, and a the keyhole in it.

B is a flat plate of oval or eccentric outline having a rectangular open slot b^x in one side and a lever or straight member B^x on one 65 side of such slot. This piece B is secured to the front face of the escutcheon-plate by means of a screw or a rivet C , on which as a pivot or center it is fitted to turn closely against the face of the before-mentioned plate. 70 This center of movement is placed below the keyhole-aperture a and preferably on the vertical center line of the aperture, and the pivot is also located eccentrically in the piece B with respect to the curved edge b , so that the 75 longer axis of the plate B being equal at least to the shortest distance between the pivot C and the top of the keyhole-aperture that opening will be covered by the plate B when it is turned on its pivot a sufficient distance. 80

The open slot is situated on the side of the shorter axis of the plate and is made of proper width to expose the keyhole-aperture, the lower portion of which would be covered by that part of the plate if the before-mentioned 85 slot were not cut in the plate. From this open slot the edge b of the plate is formed on a spiral or involute curve of increasing radius from such slot around to the opposite side of the center. The lever B^x is formed integral 90 with the plate B , and its outer end is bent outward to form a handle portion b^o , standing at right angles from the face of the plate for convenience in turning the plate on its pivot.

As thus constructed and applied, it will be seen that when the plate B is set into the position represented in Fig. 1 of the drawings with the open slit in line with the keyhole-aperture of the lock there is no obstruction 95 100

in the way of properly inserting and removing the key D of the lock; but as the plate B is turned on its pivot C in the direction of the arrow x the curved edge b is caused to 5 pass across the keyhole-aperture, and if the key remains in the lock on that side of the door the edge b will come in contact with the shank of the key, and suitable degree of force being applied to the lever B^x at such time 10 to this edge of the plate will press the key-shank against the edge of the circular part of the keyhole. By this means the shank of the key is gripped between the plate B and the edge of the aperture in the escutcheon- 15 plate, and by giving the edge b sufficient pressure against it the key will be held so firmly that it cannot be turned from the opposite side of the door by any implement or device of the burglar. In this position, which is represented in Fig. 2 of the drawings, it will be 20 noticed that the backward rotary movement of the key at this time must tend only to increase the grip of the plate upon the key-shank. As the proper movement of the key 25 to draw back the bolt being necessarily in the direction of the arrow y the plate B will move in the opposite direction (indicated by the arrow z) if it moves at all. Such gripping action of the plate B is increased and made effective 30 under all conditions by forming on the shank of the key, at that part which makes contact with the edge of the plate B, a concave recess or portion d , corresponding to or approaching in its cross-section the curve of the edge b of the 35 plate, as shown in Figs. 5 and 6 of the drawings. In addition to this office and function as a key-fastener my said attachment also forms a keyhole guard or escutcheon, entirely covering the opening when it is turned

into the position represented in Fig. 3 after 40 the key has been taken out. It also constitutes a convenient means of retaining the key in the lock at other times by throwing the plate B partly around, so that the slot b is turned out of line with the keyhole. 45

Having thus fully described my invention, what I claim as new, and desire to secure by Letters Patent, is—

The herein-described key-fastening attachment for door-locks, comprising the segment- 50 shape plate B having a curvilinear edge b , a rectangular slot b^x in one side extending from the edge inward, and a straight arm or lever B^x extending from the same side of the plate and in the same plane, the edge of said lever 55 forming one side of such slot, and a hole C for a pivot-screw located to one side of the center of said plate and in close relation to the bottom of the rectangular slot as described; the said plate being pivotally attached to the escutcheon-plate of the lock at a point below and in line with the keyhole and eccentrically with relation to the curvilinear edge b as described, whereby the slot 60 in the plate is caused to register with the key-hole by turning the plate in one direction, and when turned in the opposite direction the plate is caused to cover the keyhole and its curvilinear edge to grip the shank of the key 65 in the circular part of the keyhole, as and 70 for the purpose set forth.

In testimony that I claim the foregoing I have hereunto set my hand and seal.

WILLIAM F. BLANCHET. [L. S.]
